UNITED STATES PATENT OFFICE.

WILHELM FRANS RIEMVIS, OF SOEKABOEMI, JAVA, DUTCH EAST INDIES.

AUTOMOBILE BRANCARD.

Application filed June 24, 1926, Serial No. 118,285, and in the Netherlands May 28, 1925.

The present invention relates to an automobile-brancard and has for its object to so construct the same that the brancard, without before-hand arranging stationary supports, may be mounted in an automobile.

In connection herewith an automobile brancard according to the invention is characterized by a frame with spring device for resiliently supporting a sick-litter or the like, the said frame being supported by a base or footpiece, which preferably is adjustable in vertical direction. This base or footpiece may be provided with one or more lateral supporting arms or shackles, which at the one end, that may be provided with a supporting plate, is adapted to rest on a seat of the automobile. Moreover, the frame may be connected in a tiltable manner to the base or footpiece and at the same time may be rotatable about a vertical axis. The above mentioned spring device is further constructed preferably in such a manner, that a sick litter or the like, suspended therefrom, is resiliently supported horizontally and vertically, preferably at the four corners.

The drawing illustrates the invention in some embodiments.

Fig. 1 is a side elevation of the brancard with sick-litter.

Fig. 2 is a plan view without the said litter and

Fig. 3 is a front elevation with the said litter.

Fig. 4 is a perspective showing of another brancard.

Fig. 5 is a plan view of this brancard.

The brancard is carried by a base comprising a column 2 provided with a supporting plate 1, the said column resting on the floor of the coach-work of a motor-car, while it rests by means of the hinge-plate 3 of a longitudinal arm or shackle 4 on the back seat underneath the cushion. The column 2 is hollow and adapted to receive the screw spindle, 19, pivotally carried by the projection 20 or a bridge piece 21 which supports the longitudinal girders 6, interconnected at the ends by hook-irons 7 and constituting a support for a pair of channel-irons 8, functioning as rails.

To the above described frame two semi-circular supporting springs 9 are secured at either side, cooperating with clamping elements 10 for the sick-litter 11, which is provided with four feet 12, one pair of which is provided with rollers 13. A pair of arms stationary supporting points.

14 is provided for each of the springs 9, each pair of arms being pivotally connected at one end together, and connected at the other ends to opposite sides of the springs 9. The arms 14 tend to inhibit torsional lateral diversion of the spring. For each pair of arms 14, a helical spring 15 is provided axially of the pivotal connection of said arms, and tending to bias said arms toward one another. These 65 springs provide for a controlled degree of lateral deflection of the springs 9.

The operation of the new brancard is very simple. The sick-litter 11 is detached from the clamping elements 10, which are provided with clamping screws, and by means of the feet 12 or other means is shifted longitudinally, the rollers 13 running upwards on the rails 8 until at the other end, the litter may be lifted off. The sick or wounded person is 75 laid on the litter, whereupon the latter is rolled back and locked in position. In order to facilitate the rolling on and off operation the whole may be rotated sideways about the axis of the screw-spindle, transversely of the 80 motorcar, and at the same time may be tilted more or less forwardly or backwardly.

The sick-litter once being slid on the frame, then the latter is turned back in the longitudinal direction of the motorcar, whereupon 85 it is lowered by means of the screw spindle 20 19, which is operated by handle 23, so far till it rests again on the back of the seat.

Figs. 4 and 5 illustrate an improved construction, in which besides the hollow column 90 2 still more supporting tubes 16 are attached to the base plate 1. The plate 3 which comes to rest on the seat, underneath the cushion or in the place of the latter, is here substituted by a collapsible or foldable framework 17 95 (see Fig. 4). The adjustable support is further provided with an additional shackle 18, adapted to be swung upwards. Further structural modifications of minor importance appear clearly from the drawings and need 100 no further description.

If desired the frame of the brancard together with the springs may be removed from the adjustable support and then be used for the transport of sick or wounded persons, 105 with or without employing stationary supports in aeroplanes, railway-carriages or other vehicles.

Thus a very practical device is obtained adapted to be manufactured at low costs and 110 suitable for use anywhere without needing stationary supporting points.

I claim:

1. A brancard support including a frame, leaf springs of semi-circular shape, mounted on said frame adjacent its opposite ends, the 5 free ends of said springs being oscillatable in vertical planes, and by torsion, horizontally, clamping means for a brancard carried by the free ends of said springs, a pair of rigid arms for each spring, having a common pivotal 10 connection and connected to said springs at points at opposite sides of its arc of curvature, tending to inhibit torsional deflection of said spring, and a spring normally biasing 15 said arms together axially of said pivotal connection, for controlling the degree of lateral torsional deflection permitted by said semi-circular springs.

2. A brancard support including a frame, leaf springs of semi-circular shape, mounted 20 on said frames adjacent its opposite ends, the free ends of said springs being oscillatable in vertical planes, and by torsion, horizontally, clamping means for a brancard carried by the free ends of said springs, a pair of 25 rigid arms for each spring, having a common pivotal connection, and connected to said springs at points at opposite sides of its arc of curvature, tending to inhibit torsional deflection of said spring, a spring normally

biasing said arms together axially of said pivotal connection for controlling the degree of lateral torsional deflection permitted by 35 said semi-circular springs and a track carried by said frame for guiding said brancard into position relative to said clamping means, said track being so disposed as to be out of contact with said brancard when the latter is in position upon said clamping means.

3. A device for supporting a brancard in an ordinary passenger automobile comprising 40 a frame, a base for supporting said frame, means for adjusting said base vertically, said base having a relatively rotatable portion for rotating said frame, means on said rotatable portion for hingedly supporting said frame on a horizontal axis, a lateral arm secured to said base terminating in a plane above the plane of the lower surface of said base, adapted to rest upon a part of the automobile 45 higher than the floor, for stabilizing said frame, spring means adjacent the ends of said frame for resiliently supporting said brancard for horizontal as well as vertical displacement, and guide rails for guiding the brancard longitudinally when rolling it off 50 or on said frame.

In testimony whereof I affix my signature.

WILHELM FRANS RIEMVIS.
